FIG. 2.

Inventor
Paul H. Waller
by Herbert W. Penner
Attorney.

UNITED STATES PATENT OFFICE.

PAUL HENRY WALLER, OF CAMBERWELL, LONDON, ENGLAND.

ELECTRICALLY-OPERATED STATION-INDICATOR.

1,364,905.

Specification of Letters Patent. Patented Jan. 11, 1921.

Application filed November 10, 1919. Serial No. 336,973.

To all whom it may concern:

Be it known that I, PAUL HENRY WALLER, a citizen of the Republic of France, residing at Camberwell, in the county of London, S. E., England, (whose post-office address is 41 Wilson road, Camberwell, in the county of London, S. E., England,) have invented certain new and useful Improvements in or Relating to Electrically-Operated Station-Indicators; and I do hereby declare the following to be a full, clear, and exact description of the invention, such as will enable others skilled in the art to which it appertains to make and use the same.

15 This invention is for improvements in apparatus for exhibiting notices and the like and has for its object to provide an automatic device whereby a series of notices can be exhibited in succession.

20 According to this invention there is provided in an automatic indicator of this type the combination with a step-by-step device whereof each operation exhibits one notice, of means whereby a predetermined notice or 25 notices may be prevented from being exhibited, and the operation of the step-by-step device which would normally exhibit it or them is caused to exhibit the next succeeding notice not thus canceled.

30 According to another feature of the invention the apparatus also comprises means whereby in place of each notice predetermined for cancellation, an alternative notice is exhibited, such notice preferably being exhibited during the exhibition of the 35 whole series.

In the preferred construction the apparatus is electrically operated and comprises a switch automatically actuated to make contact with a series of contacts successively, one contact being allocated to each notice to be exhibited, and a series of manually-controlled switches one in the circuit of each contact, adjustable to connect its contact 40 either to the circuit of the notice to which it is allocated or to the next succeeding contact.

45 The exhibition of the alternative notice is effected by means of auxiliary switches movable with the above-mentioned manually-controlled switches.

In the drawings, Figure 1 is a diagram showing the arrangement of switches, and wiring used in the indicator. Fig. 2 is a front view of an indicator used in carrying out this invention.

In the drawings Figs. 1 and 2 show an

indicator arranged for five stations labeled respectively "A" "B" "C" "D" "E", and as shown in Fig. 2 the apparatus indicates either the next station or that the train is "not stopping at" any particular station. Conveniently these notices are exhibited by being mounted on translucent screens, and a lamp or lamps are switched in or out of circuit according as the notice is to be exhibited or not.

It will be understood that the invention is not limited to the particular notice illustrated but that any desired notice or any desired number of notices may be exhibited in a similar way.

Referring now to Fig. 1, the apparatus for controlling the indicator comprises a rotatable switch K arranged to sweep over a series of contacts A' B' C' D' E'. This switch K is actuated to move forward from any contact to the next succeeding one in a step-by-step movement by any desired type of mechanism. Thus it may be mechanically actuated by a ramp or other device on the track, working through a ratchet and pawl, or it may be electrically actuated by a circuit controlled, either opened or closed, by a device on the track, the general result being that the switch K is moved forward one step by the passage of the train from one station to the next.

Each of the contacts is connected to a manually-controlled switch A² B² C² D² E² respectively, and these switches normally engage contacts A³ B³ C³ D³ E³ which are in turn connected to lamps A⁴ B⁴ C⁴ D⁴ E⁴. These lamps are arranged behind the notices which normally are exhibited in succession, that is to say, in Fig. 2 behind the notice marked "Next station". The other poles of the lamps are all connected together and to one of the electric mains L, the other main M being connected to the switch K by any suitable rubbing contact.

When the manually-controlled switches are all in their normal position, it will be seen that a circuit is completed from M through the switch-arm K, through one of the contacts in the series A' B' C' D' E', through the corresponding manually-controlled switch and the corresponding lamp back to the other main L; the lamp is thus illuminated and the particular sign is exhibited.

If the train is required to stop at every station, the apparatus thus far described

- would when correctly adjusted, exhibit each notice in succession, that is to say on leaving say station "A," a notice would be exhibited that "B" is the next station. Similarly 5 on leaving "B" the switch-arm K would be moved on to the contact C' and the notice for station "B" would cease to be illuminated and the notice to the effect that "C" is the next station would be illuminated.
- 10 It is necessary however to provide for the train missing some stations, that is to say on leaving station "B" it will be required to show that "D" is the next station, and to indicate that the train does not stop at "C."
- 15 In order to accomplish this each of the manually-controlled switches is provided with auxiliary contacts as shown at C⁵ and C⁶, and the switch C² is adjustable to engage either of the three contacts C⁵ C³ C⁶. The 20 contact C⁶ is connected to the switch member or the blade of the next succeeding switch D², and the contact C⁵ is similarly connected to the next previous switch B². The use of these contacts is as follows:—
- 25 Assuming that the train is traveling from "A" toward "E" and that it is not to stop at station "C," the switch C² is moved on to the contact C⁶. On leaving the station "B" the switch K is moved on to the contact C' 30 and the circuit is completed through C' C² C⁶ D² D³ and the lamp D⁴ thereby exhibiting the notice that "D" is the next station, and preventing the notice "C" "Next station" from being exhibited. When the train 35 passes station "C," the switch K is moved on to the contact D' and the circuit is completed through D' D² D³ D⁴ so that the notice remains unchanged until the station "D" is reached.
- 40 In addition to preventing the exhibition of a notice, it is desirable to exhibit a definite notice to the effect that the train does not stop at any particular station and according to another feature of the invention, 45 this is effected by a series of auxiliary switches A⁷ B⁷ C⁷ D⁷ E⁷. These switches are preferably mechanically interconnected with the manually-controlled switches A² and they are provided with two contacts C⁸ C⁹, these contacts being spaced sufficiently 50 far apart to allow the switch blade C' to lie in between them without making contact with either. The contacts C⁸ C⁹ are so disposed that when the manually-controlled switch C² is in its normal position, that is to say, in contact with C⁵, then the auxiliary switch C⁷ is lying between the contacts C⁸ and C⁹ and does not complete any circuit.
- 55 When however, the switch C² is moved to engage either of the contacts C⁵ C⁶, then the switch C⁷ is moved with it to engage one or other of the contacts C⁸ C⁹. The pairs of contacts C⁸ C⁹ for each of the auxiliary switches are connected together and to one of 60 the series of lamps A¹⁰ B¹⁰ C¹⁰ D¹⁰ E¹⁰, and

these lamps are used to illuminate the notice shown in Fig. 2 "Not stopping at." The other poles of these lamps are all connected together to the main L and the switch-arms A⁷ B⁷ C⁷ D⁷ E⁷ are similarly all connected 70 to the main M. It will be seen, therefore, that when these switches are each in their central position no circuit is completed, but when moved in either direction by the operation of one of the manually-controlled 75 switches, a circuit is completed from the main M through one of the lamps A¹⁰ B¹⁰ C¹⁰ D¹⁰ E¹⁰ illuminating the respective notices.

When the train is due to commence its 80 journey from "A" and it is to miss certain stations, say "C" on the journey, the switch C² is moved upward to make contact with C⁶ as described above. The switch C⁷ is thereby moved on to the contact C⁹ and the 85 notice C¹⁰ is illuminated. Therefore from the beginning of the journey there is a notice shown to the effect that the train is "Not stopping at C." The switch K operates in the manner above described indicating the 90 next station in turn, until leaving "B" when it indicates that the next station is "D" as above described. It will be seen, therefore, that the apparatus is automatic after the 95 manually-controlled switches have been adjusted at the beginning of the journey.

In order to provide for the return journey from "E" to "A" without reversing the operation of the step-by-step switch K, additional contacts d¹ c¹ b¹ are provided, so that 100 the switch K on leaving contact E¹ (on the return journey of the train) is by the normal operation moved on to the contact d¹. This contact is connected to the contact D¹ so that the circuit for exhibiting the notice 105 is the same as previously described. In order to provide for missing stations on the return journey, the second set of contacts as at C⁵ are provided for the manually-controlled switches A² B² C² D² E², these contacts being connected to the next previous 110 switch as above described. On the return journey, therefore, if any station say "C," is to be passed, the corresponding manually-operated switch C² is moved to its lower 115 position making contact with C⁵. When the switch K makes contact with c¹, the circuit is completed therefrom through C¹ C² C⁵ B² B³ B⁴ thereby exhibiting the notice that "B" 120 is the next station. This operation of the switch C² has simultaneously moved the switch C⁷ on to the contact C⁸ to exhibit the notice that the train is "not stopping at C," and this notice is, as before, exhibited 125 throughout the whole journey.

In order to provide for the train not making a full journey from "A" to "E" but say, stopping at "C" and then returning to "A," any convenient means may be provided for manually operating the switch K in the 130

series of steps. When the train stops at "C," with the switch K on the contact C¹ all that is required is that before it commences its return journey, the switch K 5 should be moved around to the contact C¹; this it will be noted is the position which the switch would normally occupy at that station on the return journey.

It will be appreciated that any number 10 of notices may be controlled by a single set of switches, so that the one apparatus on a train could control a series of notices distributed throughout the train. Also it will be appreciated that any desired type of 15 switch may be used, together with any desired type of indicator and that the notices may be exhibited in other ways than by illuminating them, if so desired, without departing from the scope of the present invention. 20

What I claim as my invention and desire to secure by Letters Patent is:—

1. In an indicator, a series of notices, electric circuits provided with a switch 25 provided with a series of contacts and operating to exhibit the said notices automatically and one after another in regular order, and manually controlled switches included in the said circuits, each manually controlled 30 switch operating to open the circuit to which it pertains and connect it with one of the other circuits.

2. In an indicator, a series of notices, electric circuits provided with a switch provided with a series of contacts and operating to 35 exhibit the said notices automatically and one after another in regular order, and manually controlled switches included in the said circuits, each manually controlled switch operating to open the circuit of the 40 notice to which it pertains and connect it with either of the circuits pertaining to the notices next before and next after it in the series.

3. In an indicator, a series of notices, electric circuits provided with a main switch provided with a series of contacts and operating to 45 exhibit the said notices automatically and one after another in regular order, manually controlled switches included in the 50 said circuits, each manually controlled switch operating to open the circuit of the notice to which it pertains and connect it with one of the other circuits, a series of 55 alternative notices, electric circuits operating to exhibit the alternative notices, and manually operated switches for opening and closing the circuits of the alternative notices.

In testimony whereof I have affixed my signature, in presence of two witnesses.

PAUL HENRY WALLER.
